UNITED STATES PATENT OFFICE.

GLENN E. McFADDEN, OF KANSAS CITY, MISSOURI.

DESIGN FOR AN ELECTRIC-LIGHTING WALL FIXTURE OR SIMILAR ARTICLE.

Application filed August 10, 1927. Serial No. 23,053. Term of patent 7 years.

To all whom it may concern:

Be it known that I, GLENN E. McFADDEN, a citizen of the United States, residing at 315 East Winthrop Road, Kansas City, Missouri, have invented a new, original, and ornamental Design for an Electric-Lighting Wall Fixture or Similar Article, of which the following is a specification, reference being had to the accompanying drawing, forming a part hereof.

Figure #1 in the accompanying drawing is a front view of an electric lighting wall

fixture or similar article, showing my new design.

Figure #2 is a diagrammatic fragmentary side view.

Figure #3 is a fragmentary bottom plan view of the fixture shown in Figure 1.

I claim:

The ornamental design for an electric lighting wall fixture, or similar article, substantially as shown.

GLENN E. McFADDEN.
